United States Patent Office

Des. 227,126
Patented June 5, 1973

227,126

ANIMAL CARRYING CASE

Robert L. Brison, Glendora, Calif., assignor to Whittaker Corporation

Filed Aug. 23, 1971, Ser. No. 174,288

Term of patent 14 years

Int. Cl. D30—02

U.S. Cl. D30—1

FIG.-1

FIG.-5

FIG.-6

FIG. 1 is a perspective view of an animal carrying case, showing my new design;

FIG. 2 is an end elevational view;

FIG. 3 is a side elevational view;

FIG. 4 is an opposite end elevational view;

FIG. 5 is a top plan view; and

FIG. 6 is a bottom plan view thereof.

I claim:

The ornamental design for an animal carrying case, as shown.
